US00D848432S

(12) **United States Design Patent** (10) Patent No.: **US D848,432 S**
Lim et al. (45) Date of Patent: **** May 14, 2019**

(54) **SSD STORAGE DEVICE**

(71) Applicant: **SAMSUNG ELECTRONICS CO., LTD.**, Suwon-si (KR)

(72) Inventors: **G. M Lim**, Seoul (KR); **Eun-jin Yun**, Seoul (KR); **Hyuk-jun Yoo**, Hwaseong-si (KR)

(73) Assignee: **SAMSUNG ELECTRONICS CO., LTD.**, Suwon-si (KR)

(**) Term: **15 Years**

(21) Appl. No.: **29/614,243**

(22) Filed: **Aug. 17, 2017**

(30) **Foreign Application Priority Data**

Feb. 17, 2017 (KR) 30-2017-0007652

(51) LOC (11) Cl. **14-02**
